UNITED STATES PATENT OFFICE.

JOHN W. HIGGINS, OF AKRON, OHIO, ASSIGNOR TO THE B. F. GOODRICH COMPANY, OF NEW YORK, N. Y., A CORPORATION OF NEW YORK.

DESIGN FOR A BATHING CAP.

Application filed December 18, 1925. Serial No. 15,780. Term of patent 14 years.

To all whom it may concern:

Be it known that I, JOHN W. HIGGINS, a citizen of the United States, residing at Akron, in the county of Summit and State of Ohio, have invented a new, original, and ornamental Design for a Bathing Cap, of which the following is a specification, reference being had to the accompanying drawing, forming a part thereof.

Fig. 1 is a side elevation of a bathing cap showing my design.

Fig. 2 is a top plan or edge view thereof.

I claim:

The ornamental design for a bathing cap as shown.

JOHN W. HIGGINS.
